UNITED STATES PATENT OFFICE.

JAMES E. POTTER, OF PROVIDENCE, RHODE ISLAND, ASSIGNOR TO A & Z CHAIN CO.,
OF PROVIDENCE, RHODE ISLAND, A CORPORATION OF RHODE ISLAND.

YIELDABLE EXTENSION MEMBER.

Application filed March 4, 1924. Serial No. 696,913.

This invention relates to improvements in extendible members for bracelets and the like; and has for its object to provide an extendible member of this character having 5 a body portion with a spring-pressed, normally-contracted sliding member mounted therein, both said body and said member having means by which they may be attached to opposite ends of a bracelet whereby the 10 bracelet is adapted to be extended or yieldably enlarged or elongated as desired.

With these and other objects in view, the invention consists of certain novel features of construction, as will be more fully described, and particularly pointed out in the appended claims.

In the accompanying drawings:

Figure 1 is a side elevation showing my improved extendible member as connected 20 to a watch bracelet.

Figure 2 is a detail showing a perspective view of the body member of the device.

Figure 3 is a detail showing a perspective view of the extendible or slidable member of the device.

Figure 4 is a perspective view showing the back plate and end plate of the body member.

Figure 5 is an enlarged section on line 5-5 of Figure 6 showing the edges of the side walls as rolled over the back plate to lock the same in the body.

Figure 6 is a longitudinal sectional view 25 of the body member and the slide member mounted therein, the two being somewhat extended relatively.

Figure 7 is a perspective view showing 40 a portion of the back plate broken away and the slide member partially extended.

It is found in practice of advantage to provide an extendible member for bracelets such as a wrist watch, bracelet, and the like in which ribbon or strips of flexible but non- 45 extendible material may be employed for the purpose of rendering such a bracelet extendible to some extent whereby it may be elongated or enlarged to slip over the hand of the wearer or to adjust itself and cling 50 to the wrist as desired; and the following is a detailed description of my improved construction of extendible member by which these advantageous results may be obtained.

With reference to the drawings, 10 designates the body portion of my improved ex-

tendible member which is preferably formed of sheet stock having a front plate 11 and two side walls 12 also a one end a tongue member 13 is formed which may be bent up into loop shape to connect the body to the 60 next adjacent element of the bracelet.

Fitted to slide between the side walls 12 of this body member is the slide member 14 which is provided with a back plate or wall 15, side walls 16 and an end wall 17. 65

Connected to the back plate 15 on the end opposite the end wall 17 is an extending tongue 18 adapted to be rolled or folded up into an eye-form to be connected to the next adjacent element of the chain 70 or bracelet.

In order to secure the slide member 14 in the body member and in slidable relation therewith, I have provided a back plate 19 which is secured between the side walls 12 75 of the body by rolling the edges 20 of these walls over those of the back plate. This back plate is provided with an integral, inwardly-extending end wall 21 which is cut away at its edges 22 to permit the passage 80 of the side walls 16 of the slide member 14.

In assembling these parts I first insert the slide member 14 into the body member 10 and then position a coiled spring 23 so that one end will abut against the end wall 17 85 of the slide member and its opposite end will abut against the end wall 21 of the back plate which is then inserted. This back plate is then secured in position by rolling the edges 20 thereover and the device is 90 completed.

In applying this complete device to a bracelet it is only necessary to provide loop or bail members 24 and 13 in opposite ends of the bracelet and connect them to the eye 95 members 13 and 18 of my improved device which will permit an extendible or flexible action to an otherwise non-extendible bracelet.

The foregoing description is directed solely towards the construction illustrated, but I desire it to be understood that I reserve the privilege of resorting to all the mechanical changes to which the device is susceptible, the invention being defined and limited 105 only by the terms of the appended claims.

I claim:

1. An extension member for a bracelet or the like, comprising a sheet-metal hollow substantially rectangular box like body hav- 110

- ing front, back and side walls and one end wall, a sheet metal slide in said body extending out through said end wall, an abutment on that portion of said slide within said body, a spring acting between said abutment and end wall to draw said slide within said body, and means for attaching said slide and body to opposite portions of a bracelet.
19. 2. An extendible member for a bracelet comprising a sheet metal trough-shaped member, a back plate attached thereto forming a hollow body, an end wall on said back plate extending into said trough, a 15 slide member extending from said trough-shaped member and having an end wall, attaching means carried by each of said members for engaging portions of a bracelet, and a spring acting between said end walls to draw said walls to draw said attaching means

toward each other for contracting the bracelet.

3. An extendible unit for a bracket comprising a sheet-metal trough-shaped member, a back plate secured thereto by rolling the edges of the side walls of said member thereover, an end wall on said back plate extending into the trough of said member, a second, slidably trough-shaped member slidably extending from said first trough-shaped member and having an end wall, a tongue carried by each of said members for engaging portions of a bracelet, and a spring acting between said end walls to draw said tongues toward each other for contracting the bracelet.

In testimony whereof I affix my signature.

JAMES E. POTTER.
